UNITED STATES PATENT OFFICE.

FRANK F. LANDIS, OF WAYNESBOROUGH, PENNSYLVANIA.

STEAM-BOILER.

SPECIFICATION forming part of Letters Patent No. 372,855, dated November 8, 1887.

Application filed January 18, 1886. Serial No. 188,895. (No model.)

To all whom it may concern:

Be it known that I, FRANK F. LANDIS, a citizen of the United States, residing at Waynesborough, in the county of Franklin and State 5 of Pennsylvania, have invented certain new and useful Improvements in Steam-Boilers, of which the following is a specification, reference being had therein to the accompanying drawings.

10 My invention relates to improvements in steam-boilers for traction-engines or boilers subjected to motion and changes in their level; and the objects of my improvements are to produce a boiler that can be easily taken care 15 of by inexperienced persons, and at the same time possessing lightness and great strength, containing a small quantity of water at a time, but still covering the crown-sheet to a good depth, whatever may be the level of the boiler 20 in descending hills. It is an improvement upon the steam-boiler for which I obtained a patent January 30, 1883, No. 271,477, and although said boiler meets all the requirements 25 of a traction-engine traveling upon level or hilly roads, as very little steam is used in descending hills, it may yet happen that if said engine is used in plowing and has to expend much steam while working in descending a 30 long hill the level of the water around the fire-box may be so lowered as to expose the crown-sheet before reaching a level piece of ground, and thus having a good depth of water re- stored above the crown-sheet.

The object of the present improvement is 35 to prevent the often violent ebullition in the rear of the steam-chamber at the point where the steam escapes from around the fire-flues by increasing the number of escape-openings and shortening the path followed by the steam. 40 I attain these objects by the construction illustrated in the accompanying drawings, in which—

Figure 1 is a longitudinal vertical section of 45 a boiler constructed in accordance with my invention. Fig. 2 is a transverse vertical section of the same through line xx of Fig. 1. Fig. 3 is a transverse vertical section through the steam-passage on line y of Fig. 1. Fig. 4 is a longitudinal vertical section of a boiler, 50 showing my invention slightly modified in form. Fig. 5 is a transverse vertical section on line xx of Fig. 4. Fig. 6 is a transverse vertical

section through the steam-passage on line yy of Fig. 4. Fig. 7 is a vertical section of a steam-passage made with a flaring entrance. 55 Fig. 8 is a longitudinal vertical section of a boiler, showing my invention slightly modified in form. Fig. 9 is a transverse vertical section on line xx of Fig. 8. Fig. 10 is a vertical section, on a large scale, of a hollow screw-plug and a fusible ball dropped and also compressed therein. Fig. 11 is a side view of a ramrod and conical fusible plug.

In said drawings, A represents the fire-box; B, the crown-sheet; C, the flues; D, the stationary lower portion of the stack; E, the steam-dome, and F' the steam-supply pipe, all of the usual construction.

G represents a horizontal partition located somewhat above the center of the boiler and 65 above the flues, and suitably secured to the shell of the boiler proper. The front end of the horizontal partition terminates a short distance in the rear of the front flue-sheet, H, where a substantially semicircular flanged 70 head, I, is secured to it and to the shell of the boiler. The rear end of the horizontal partition extends nearly to the seam uniting the fire-box and flue portions of the boiler, and is 75 partially closed by the head I', secured thereto and to the shell. The upper edge of the rear head, I', terminates in a rearwardly-projecting flange, i, to arrest in part the water that may surge against said rear head. The horizontal partition and the two heads form, in connection with the shell, a chamber, G', separate 80 from the flue portion of the boiler, and directly communicating with the steam-dome, and also limiting the forward end of a second compartment, B', immediately over the crown-sheet B, through which compartment extends 85 a substantially horizontal pipe, J, one end of which is secured in the head I', adjacent to the bottom of the chamber G', for the escape of water entering said chamber. 90

Near the top of the forward head, I, and secured therein, is a pipe, P. (Shown in dotted lines in Fig. 1 and in full lines in Fig. 4.) It communicates with the forward end of the flue-chamber of the boiler and extends rearwardly to within a short distance of the rear end of the boiler, where it discharges steam close to the under side of the shell of the boiler. 95 100

At some point between the center of the length of the chamber G' and the rear head, I' , there is riveted transversely to the bottom G a narrow antechamber or steam-receiving chamber, K , one shape of which is shown in Fig. 3, being a section on line y of Fig. 1. The bottom of the chamber K is open, and communicates with the flue-space under the bottom G , said bottom being cut through at that point to form an opening having the length and width of the chamber K . To the rear wall of this chamber, and at the highest point thereof, as shown in Fig. 3, is secured a pipe, L , that also extends to within a short distance 15 of the rear end of the boiler for the purpose of taking to that point the steam that is generated from the flue-surface under that part of the bottom between the opening under the chamber K and the front head, I , of the boiler while pulling down hill, and therefore only one-half of the steam generated under the bottom G will escape through the space between the fire-box and the rear head, I' , and the steam-agitation at that point will be 25 much less violent; and while going up hill the steam from the tube-surface between the fire-box and the chamber K will escape through the chamber K and pipe L , and will reduce the agitation at the front end.

30 In the forward portion of the steam-pipes P and L small perforations e are made in the upper surface, to allow the steam to escape therethrough close under the highest point in the boiler, even if the rear ends of said pipes were covered with water, as when ascending a very steep grade.

35 The invention has been described as shown in Figs. 1, 2, 3; but I prefer the form and arrangement shown in Figs. 4, 5, 6, as being 40 simpler and still more effectual in overcoming the trouble caused by the steam issuing through the water-surface close to the rear partition, I' .

In the last-stated figures the partition I' 45 forms the rear wall of the chamber K , and it has a pendent flange, F , which extends down to the top of the upper row of flues, C . This flange F will cause nearly all the steam from the entire tube-surface to pass up through the 50 chamber K . The pipe J is fastened into a sleeve that passes through both walls of the chamber K , while the pipe L extends only through the highest part of the rear wall, I' , of said chamber. Instead of making the walls 55 of the chamber K parallel, they may be placed at an angle to each other, or the front wall inclined, so that the chamber will be wider at the bottom, as shown in Fig. 7, to facilitate the entrance of the steam generated under the 60 floor G .

In the boiler shown in Figs. 8 and 9 the steam drum is well forward, as in my former patent; but it has, about half-way of its steam-chamber G , a narrow transverse steam-receiving chamber, K , as described in regard to Fig. 1, and through the walls of said cham-

ber passes a pipe, J , to drain toward the rear the water that may enter into the forward compartment. The partition I' of the rear compartment has also a pipe, J' , passing there-through for the same purpose. 70

It sometimes happens that when a traction-engine is on the road it will get so short of water that the crown sheet will be uncovered and the fusible plug secured in said 75 crown sheet will become melted. It is then difficult to have a new one inserted, as the fire must be all drawn out from the fire-box and the boiler left to cool, and the engine-driver must either enter the fire-box and unscrew the plug B^2 , to insert a new fusible plug, b , or he must open a hand-hole for the same purpose, and by either means it causes a long de-tention. To obviate this I prefer to use a screw-tapped plug, B^2 , having its upper end pro- 80 vided with a cavity to receive a plug of soft metal, preferably in the form of a ball, b , or a slightly-conical plug, b' . The cavity in the screw tapped plug B^2 is preferably provided with an annular groove, b^3 , to receive a por- 85 tion of the soft metal when forced therein with a ramrod, B^3 , and thereby retain the fusible plug when the boiler cools, the lower tempera-ture causing a vacuum in the boiler; and in line with the axis of the hole made in the 90 crown-sheet to receive the plug B^2 another hole is made in the shell of the boiler, both holes being cut and screw-threaded at the same time, and in the upper hole is inserted a tube, b^2 , of such length that it will extend to within 100 about a quarter of an inch from the plug B^2 , and through this tube a new fusible plug can be dropped into the opening of the plug B^2 and driven therein with a round bar of iron having its end flat. The bar or ramrod is then 105 removed and the upper end of the tube b^2 closed with a solid screw-threaded plug, b^5 , and all is ready to start on the road again.

Although I have shown and fully described a fusible plug and its mode of insertion in and attachment to a boiler, I make no claim thereto in the present case.

Having now fully described my invention and its operation, I claim—

1. In a steam-boiler constructed with flues, 115 a compartment having a floor located above said flues to arrest a body of water, an opening in this floor leading into a passage having side walls united at the top and extending into said compartment, and provided with an 120 opening in the rear wall of said passage, sub-stantially as described.

2. In a steam-boiler constructed with flues, a compartment having a floor located above said flues, an opening in the floor, a passage 125 having side walls extending up into said compartment, and a water-discharging pipe, J , issuing from the rear of said compartment, substantially as and for the purpose described.

3. In a steam-boiler, a compartment having 130 a floor located under the steam-dome, a head at each end, and a pipe, P , passing through

both heads, substantially as and for the purpose described.

4. In a steam-boiler constructed with flues, a compartment having a floor located above said flues, a head at each end and between said heads a chamber having an opening into the floor of the compartment, and a pipe, L, extending out from the rear of said chamber, substantially as and for the purpose described.
- 5 5. In a steam-boiler constructed with flues, a compartment having a floor located above said flues, a head at each end and between said heads a chamber having an opening into the floor of the compartment, and a flange, F, 10 pendent from said floor adjacent to said open-

ing, substantially as and for the purpose described.

6. A chamber, K, having an open bottom, a flange, as F, under the rear wall thereof, and extending down to the top of the flues of a 20 boiler, a pipe, J, passing through both walls of said chamber, and a pipe, as L, inserted into the rear head only of said chamber, substantially as and for the purpose described.

In testimony whereof I affix my signature in 25 presence of two witnesses.

FRANK F. LANDIS.
